UNITED STATES PATENT OFFICE.

GEORGE R. WOOD, OF LOS ANGELES, CALIFORNIA.

SIGN.

Application filed March 12, 1924. Serial No. 698,665.

To all whom it may concern:

Be it known that I, GEORGE R. Wood, a citizen of the United States, residing at Los Angeles, in the county of Los Angeles and State of California, have invented a new and useful Improvement in Signs, of which the following is a specification.

This invention relates to advertising signs, and an object of the invention is to provide a neat, pleasing and inexpensive sign, that can be made and sold cheaply.

Another object is to provide a sign that is constructed so that through its novel arrangement and formation it will attract attention to the advertising subject matter thereon.

Another object is to provide a sign that is easy to arrange and install for advertising; that is, the sign is provided with a hanger by which it can be detachably supported on a hook or nail arranged in a wall or secured to a stake that is especially constructed and arranged to be driven into the ground at points best suited for attracting the attention of passing persons.

Another object is to provide a sign that is especially adapted for use of realtors who require numerous cheap and inexpensive signs to advertise their lots, lands and houses; which signs must be out in the open exposed to the weather. To that end, I provide a sign with a widely extended rim that protects the lettering of the advertising from the rain; and the sign board is preferably formed of metal that is not easily tarnished or affected by climatic conditions; and when erected in an open place, as a field, it will remain for a long time in a good state of preservation.

As a special feature for advertising real estate the appliance is provided with two plates; the larger upper one being for the purpose of advertising the property for sale, and the real estate, persons, firm, or corporation in charge of the property; and the lower smaller sign being for the purpose of indicating that the property has been sold, and to also advertise the agent by whom it was sold.

An object of this invention is to provide a sign that is so inexpensive that one can be placed on every lot of a subdivision; and each sign comprises a stake and a larger pan on which is printed all information relative to the sale conditions of the lots or parcels of land, together with the title of the property, subdivision, section and the number of the lot on which the sign is erected.

Also a space is arranged on the stake for the smaller pan so that when the lot is sold, the selling agent can attach a small pan to indicate that the lot is sold; and also advertise that he has sold it.

An object is to provide a sign that is constructed and arranged so that light is reflected therefrom that will attract attention to the sign.

Features of the invention are shown in the construction, combination and arrangement of parts whereby a sign of great usefulness and pleasing appearance is provided.

Other objects, advantages and features of invention may appear from the accompanying drawing; the subjoined detailed description and the appended claims.

The accompanying drawing illustrates the invention.

Fig. 1 is a front view of a sign constructed in accordance with this invention; showing the supporting stake inserted in a fragmental portion of ground.

Fig. 2 is a central vertical section on line α^2 , Fig. 1.

Fig. 3 is a cross section on line α^3 , Fig. 1.

Fig. 4 is a view analogous to the upper portion of Fig. 1, showing the sign as adapted for use in a subdivision of land.

Fig. 5 is a central section through an advertising pan showing it provided with a strap by which it can be suspended as to a nail in a wall.

Fig. 6 is a front view of a rectangular advertising pan; showing it provided with hanger straps adapted to be attached to support such as nails and the like.

Fig. 7 is a slightly enlarged rear view of the upper pan shown in Fig. 4.

Fig. 8 shows a stake provided with upper

and lower pans arranged oppositely to one another.

Fig. 9 is an enlarged fragmental view of a stake showing a detail of the cap and 5 sheathed point.

The sign comprises a pan 1 that can be either circular or rectangular.

Preferably the pan 1 is similar in construction to an ordinary pie or cake pan.

10 It has a flat bottom 2 around which extends the angular or rectangular wall 3 and rim 4; and advertising matter is displayed on both the inside and outside of the bottom 2.

15 The advertising can be printed or impressed on the pan in any well known way such as printing, stenciling, hand painting or embossing, and the advertising can consist of any suitable subject matter and be arranged in any desired way; that shown 20 in the drawing being only for the purpose of illustration.

When the pan 1 is to be used in advertising real estate and matters pertaining thereto, it is preferably attached to a stake 5 by 25 nails or screws 6 and arranged adjacent the top end of the stake that is recessed at 7 to receive the bottom of the pan 1.

30 The stake 5 is preferably provided with a metal cap 8 that prevents the wooden stake from splitting when driven in the ground, and the lower end of the stake is provided with a sheath metal point 9 so that it can easily be driven into hard ground 10.

35 It is understood that I may employ any kind of a stake or post to support the pan 1; but the stake is preferably constructed and arranged as shown in the drawing.

40 As previously indicated the upper pan 1 is for the purpose of advertising and distinguishing the property for sales as best indicated in Fig. 4, in which the subdivision, section and lot are given; and the lower and smaller pan 1' is preferably for the 45 purpose of indicating that the lot or property on which it is located is sold and by whom the sale was made.

50 In use on a subdivision I prefer to locate a stake 5 on each parcel of land to be sold; and this stake at first carries only the upper larger pan that has a description thereon of the property and the name of the subdividing individual, company or corporation together with such data that will aid both the agents and purchasers; and I recess the 55 stake at 11 so that the smaller pan 1' can be set in and attached to the stake 5 by the salesman as soon as the parcel of land on which it is located is sold, thereby indicating to other salesmen that the property has been sold and also advertising the person, company or corporation by whom the sale has been made.

60 I may provide the stakes 5 with oppositely arranged recesses 7, 11 so that two of

the pans 1 and 1' can be arranged with their 65 bottoms adjacent to one another and secured to the stake as shown in Fig. 8.

It is also understood that I may provide the pan 1 with a strap 12 having an opening 13 therethrough that is adapted to be supported on a hanger, such as a nail 14 extending into a wall 15 as indicated in Fig. 5; it being understood that each pan can be provided with one or more of the straps 12 as indicated in Fig. 6. 70 75

It is also understood that I may employ various colors to ornament the pans 1, 1' to make them pleasing and attractive; also I may make the pans of aluminum and polish them in order that their unprinted surfaces 80 may reflect the light and attract attention to the sign; or the rim only may be polished so that it reflects its light around the advertising on the pan.

In practice the pans 1, 1' are constructed 85 as shown carrying any desired advertising matter and supported either by the stake 5 or hanger 12 in position to display the advertising.

Preferably the cap 8 and sheath point 9 90 are secured to the stake 5 as shown in Fig. 9. As shown therein the metal cap is punched into the wood as at 16, and if desired nails 17, 18 can be driven through one or more of the punched holes 16. 95

I claim:

1. The improvement in signs set forth comprising a wooden stake having a recess 100 therein; a metal pan adapted to be fitted into and secured in the recess of said stake; a metal point secured to one end of said stake; and a metal cap at the other end of said stake.

2. The improvement in signs set forth 105 comprising a wooden stake having a recess adjacent its upper end; a large pan adapted to be fitted into and secured in the recess of said stake; said pan adapted to have advertising thereon that describes the property to be sold and also the owner; a small pan 110 adapted to have advertising thereon that indicates that the property has been sold and the agent that made the sale; and means for attaching said smaller pan to said stake when said property has been sold. 115

3. The improvement in signs set forth comprising a wooden stake having a recess adjacent its upper end; a large metal pan adapted to be fitted into and secured in the recess of said stake; said pan adapted to have advertising thereon that indicates the nature of the property to be sold and the party, company or corporation selling the property; a metal point to said stake; a metal cap to said stake, said cap and metal point adapted to facilitate the driving of said stake into the ground; a small metal pan adapted to have advertising thereon 120 125

that indicates that the property has been sold and the name of the agents that sold the property; and means for securing said smaller pan to said stake when a sale has

5 been made.

4. The improvement in signs set forth comprising a wooden stake having oppositely arranged upper and lower recesses; a metal cap to said stake; a metal sheath point

10 to said stake; means for securing said cap

and point to said stake; and pans adapted to be secured in the recesses of said stake, said pans being adapted to have advertising matter thereon.

In testimony whereof, I have hereunto set 15
my hand at Los Angeles, California, this 4th
day of March, 1924.

GEORGE R. WOOD.

Witness:

W. M. GENTLE.
